Patented Dec. 11, 1917.

Inventor:
Gustave V. Cropsey,
By his Attorney,
Leo. W. Smith

UNITED STATES PATENT OFFICE.

GUSTAVE V. CROPSEY, OF AVERNE, NEW YORK.

WINE-SERVER.

1,249,341.

Specification of Letters Patent. Patented Dec. 11, 1917.

Application filed March 2, 1917. Serial No. 151,924.

To all whom it may concern:

Be it known that I, GUSTAVE V. CROPSEY, a citizen of the United States, and a resident of Averne, county of Queens, and State of New York, have invented certain new and useful Improvements in Wine-Servers, of which the following is a specification.

Although applicable to other uses my invention relates more particularly to means for serving still wines such as claret, port, Moselle and the like, and the object is to afford a holder adapted to support a bottle of wine in such manner that it may be conveniently decanted as required, while at the same time the label and the cork brand are presented in position for inspection by the customer.

On account of the sediment which these wines contain it is desirable that the bottles be disturbed as little as possible, so as not to agitate such sediment. As ordinarily stored these wine bottles are positioned horizontally, and when removed for immediate use it is customary to maintain this horizontal alinement of the bottle as near as possible. They have heretofore been served in wicker baskets in which the bottle reclined loosely, the basket being lifted bodily from the table in order to decant the wine. The baskets take up considerable room, do not hold the bottle securely, and are otherwise cumbersome and inconvenient to manipulate.

The invention consists in the specific construction and arrangement of parts described and claimed, distinctive features being the means for supporting and locking the bottle in slightly inclined position; the provision of rockers which facilitate the decanting of the wine; the provision of a cork holder whereby the brand may be exposed; and the open structure of the device, whereby the label on the bottle may be exposed for inspection without removing the bottle from the holder, all as hereinafter fully set forth.

In the accompanying drawings,

Figure 1, is a side elevation of my wine serving device, with a bottle positioned therein;

Fig. 2, is a top view of the parts shown in Fig. 1;

Fig. 3, is a front view of my holder, without the bottle;

Fig. 4, a rear view of the parts as shown in Fig. 3;

Fig. 5, is a top view of the device without

the bottle, and with the handle partly broken away;

Fig. 6, is a view similar to Fig. 1, illustrating the rocking of the device to decant the wine;

Fig. 7, is a detail view showing a modification in the support of the base cap.

The bottle B, is supported in my serving device with its longitudinal axis slightly inclined with relation to the horizontal so as to retain the sedimentary constituents of the wine at the bottom of the bottle. The neck of the bottle is sustained in the neck sleeve n, while the bottom of the bottle is supported in the base cap c. The latter is articulately connected with the frame work, preferably to the rear cross member c', thereof, although if preferred it may be hinged to the handle bar h, as in the modification shown in Fig. 7, and be secured by latch to the cross member c'. The arrangement shown in the other figures of the drawings is however the preferred one, as being most convenient in effecting the introduction of the bottle into position in the holder or removing it therefrom, and as utilizing the elasticity of the handle h, in maintaining the interlocking of the parts.

The neck sleeve n, is rigidly supported by arms n', n', rigidly attached to the tread members t, t, of the frame, to which the rear cross member c', is also rigidly attached. The forward end of the tread members t, t, are curved upward to form rockers t', t', so that the whole device may be tilted as indicated in Fig. 6, without removing it from the table or other support, to decant the wine. Thus the main weight of the holder and bottle is sustained by the table or other support, and the operation of pouring can be effectively controlled with greater ease and accuracy than where the bottle is held in a basket as heretofore.

The handle h, is rigidly secured at its forward end to the neck sleeve n; and near its rear end it is formed with one or more slots h', h', to accommodate the catch hook c², on the base cap c. Its medial part is bent to form the hand loop h²; and it is preferably made of elastic resilient metal so that its rear end acts as a spring latch or hasp for engagement with the catch c², on the base cap c, as above stated.

Secured to the forward cross member c'', of the frame is a cork receptacle a, in which a cork may be placed and exposed after ex-

traction from the bottle so that the customer may have visual evidence of the brand of the wine served,—said brand always being imposed on the corks of bottles containing the higher grades of wine as a guarantee of quality.

In this connection it may be noted also that the structure of the holder is such that the label on the bottle can also be readily examined without removing the bottle, the whole body of the bottle being exposed between the neck sleeve *n*, and the base cap *c*.

Provision is made for supporting the bottle at such an inclination from the horizontal that the contents will not flow out even when the bottle is full until the device is tilted forward on the rockers *t*', *t*'. This is indicated by the dotted line *x*—*x*, Fig. 1, and by Fig. 6.

20 The base cap *c*, is flanged peripherally to retain the bottom of the bottle which is seated therein. The neck sleeve *n*, and base cap *c*, conjointly hold the bottle close enough to prevent undue looseness or play of the 25 bottle when positioned therein; which latter may readily be accomplished, or the bottle removed, by the opening or turning back of said base cap *c*, on its hinge.

I do not wish to confine myself to the 30 identical form and structure of the supporting frame work shown as various modifications might be resorted to therein without departing from the spirit and intent of my invention in this respect. For instance a single broad tread might be substituted for the 35 two narrow treads *t*, *t*, with like result.

I have herein described my invention as applicable particularly to the serving of still wines, although it is obvious that the device 40 might be utilized for the serving of other non-effervescent bottled beverages, so that I do not restrict my claims in this respect.

What I claim as my invention and desire to secure by Letters Patent is,

45 1. A rockable bottle-holding and serving device of the character designated, comprising

Copies of this patent may be obtained for five cents each, by addressing the "Commissioner of Patents, Washington, D. C."

ing a rockable supporting frame, a pivoted base cap, a resilient handle, a neck-sleeve rigid with said frame and handle, and separable means for locking the base cap in position to hold a bottle in said neck-sleeve and base cap. 50

2. A rockable bottle-holding and serving device of the character designated, comprising a supporting frame with rockable tread members, a neck-sleeve rigid with said frame to engage the neck of a bottle, a hinged base cap, a resilient handle, the neck-sleeve being rigidly supported by said frame and the handle connected to the neck-sleeve, and 60 means locking the base cap and handle to clamp a bottle between the latter and the neck-sleeve.

3. A bottle holding and serving device of the character designated, comprising a supporting frame, rocker members supporting the same, a neck sleeve, a base cap, means for securing the latter in closed position, a handle, and a cork receptacle movable with said rocker members, for the purpose de- 70 scribed.

4. A bottle holding and service device of the character designated, comprising a supporting frame arranged to hold a bottle in substantially horizontal position, a neck 75 sleeve fixedly supported on said frame, a hinged base cap, means for securing the latter in closed position, said cap and sleeve being adapted to engage the bottom and neck of a bottle, and a handle movable with 80 said securing means, said supporting frame being open between said neck sleeve, base cap, and handle, so as to expose the body of a bottle seated in and between said neck sleeve and said base cap, and said handle 95 being rigid with said sleeve and extending to the base cap, for the purpose described.

GUSTAVE V. CROPSEY.
